[57] CLAIM

The ornamental design for a magnifier or similar article, as shown and described.

DESCRIPTION

FIG. 1 is a front elevational view of a magnifier or similar article showing my new design;

FIG. 2 is a top plan view thereof with the bottom view being a mirror image thereof;

FIG. 3 is a rear elevational view thereof;

FIG. 4 is a right side elevational view thereof with the opposite side being a mirror image thereof;

FIG. 5 is a front elevational view of a second embodiment of the design shown in FIG. 1;

FIG. 6 is a top plan view thereof with the bottom plan view and the right and left side elevational views being mirror images thereof; and,

FIG. 7 is a rear elevational view thereof.
